CLAIM

The ornamental design for a container cap with a pivotable spout, as shown and described.

DESCRIPTION

FIG. 1 is a right top perspective view of my new design for a container cap with a pivotable spout;

FIG. 2 is a top plan view thereof;

FIG. 3 is a front elevation thereof;

FIG. 4 is a right side elevation thereof, the left side elevation being identical thereto;

FIG. 5 is a rear elevation thereof;

FIG. 6 is a bottom plan view thereof; and,

FIG. 7 is a right top perspective showing the spout in an open position.

The broken line showing of a container is for illustrative purposes only and forms no part of the claimed design.
